GAS TURBINE PLANT

Walter Traupel, Winterthur, Switzerland, assignor to Sulzer Frères, Société Anonyme, Winterthur, Switzerland

Application July 11, 1942, Serial No. 450,521
In Switzerland December 18, 1941

3 Claims. (Cl. 60—49)

The invention relates to a gas turbine plant with at least one turbine for giving the useful output and at least one turbine for driving at least one compressor. The invention consists in that the turbines can be coupled to each other by a gear with adjustable speed ratio.

Preferably the speed ratio is altered in accordance with the useful output of the total plant. The turbines may for instance be coupled to each other by an hydraulic torque adjuster with adjustable guide apparatus, or by an electric coupling. The invention offers particular advantages when a part of the working medium moves in a closed circuit through at least one compressor and the turbine driving it, whilst another part of the working medium is taken from the closed circuit, replaced by an equivalent quantity, and used as combustion air in connection with the heating of the working medium flowing in the closed circuit. The invention thus makes it possible to prevent any inadmissible increase of speed of the compressor turbine.

The invention is further explained with the help of the drawing.

The working medium flowing in the closed circuit is led in a compressed state from the compressor 1 to the heat exchanger 2. From here a part of the working medium passes into the surface gas heater 3, after which it enters the turbine 5. The working medium flowing from the turbine 5 passes finally through the heat-exchanger 2 and over the cooler 7 again into the compressor 1.

From the circuit just described, a part of the working medium is tapped off and led through the pipe 4 into the combustion space of the gas heater 3, from where the combustion gases flow into the turbine 6 and finally pass away to atmosphere.

For replacing the working medium withdrawn from the closed circuit through the pipe 4, air is drawn in by the compressor 8 and mixed in a compressed state in the heat-exchanger 2 with the working medium in the closed circuit. For regulating the quantity of air delivered by the compressor 8 a greater or smaller quantity of air can be led back into the suction pipe of the compressor 8 through the bypass pipe 9 which is fitted with a valve 10.

The turbine 5 drives the main compressor 1 and the precompressor 8, whilst the turbine 6 drives the ship's propeller 12 through the toothed wheels 19 and 20. The electric motor 11 serves for starting up the plant.

Between the turbine 5 and the toothed wheels 55

18 and 20 an hydraulic gear with adjustable speed ratio is fitted; by means of it the turbine 5 and the turbine 6 can be coupled to each other. The coupling is provided with a blade wheel 14 keyed to the shaft of the turbine, and with a blade wheel 15 keyed to the shaft of the pinion 18. Between the blade wheels 14 and 15 is a guide apparatus 16 with adjustable blades which can be set in accordance with the working conditions by means of the regulating device 17.

With the help of the precompressor 8 the closed circuit leading through the compressor 1, the gas heater 3 and the turbine 5 is charged up to a pressure level, the height of which depends on the amount of load on the plant at the moment. With a high output from the plant, a higher pressure level is used than with a small output. Simultaneously with the changing of the height of the pressure level, the fuel delivery to the air heater 3 and the quantity of air removed from the circuit through the pipe 4 for burning in the air heater are adjusted in accordance.

The plant is worked in such a way that the temperature of the working medium passing into the turbine 5 remains unchanged within a wide range of load. When the pressure level is low, the turbine 5, and therefore also the compressors 1 and 8, run at a higher speed than when the pressure level is higher. The adjustability of this shaft speed is a drawback to the working of the plant in so far that the efficiency of the whole plant is only favourable within a small range of load, but falls away quickly outside that range. Further, with the considerably increased speed of the turbine 5, which occurs when the load is reduced, the turbine runner is stressed to a much greater extent.

These drawbacks can be avoided when means for transmitting power are provided between turbine 5 and turbine 6, such that the turbine 5 of the compressors 1 and 8 can rotate at the speed most favourable for them, quite independent from the speed of the turbine 6. By adjusting the guide blades 16 it is possible to transmit the power, either from the turbine 5 to the turbine 6 or vice versa, in such a way that the turbine 5 runs at the speed which is most favourable for it and for the compressors 1 and 8.

This prevents the speed of the turbine 5 rising inadmissibly high when the load is reduced or falling too low when the load is increased. Working can in fact be adjusted in such a way that the speed falls when the load is low and rises when the load is greater. In this way the efficiency is raised, so that it remains practically unchanged.

over a wide range of load and then falls only slowly.

Instead of an hydraulic gear, an electric or a mechanical gear could be adopted. Also with an electro-magnetic coupling, or with a simple hydraulic coupling with out guide apparatus, transmission of power could be obtained with adjustable speed ratio in the sense of the invention.

I claim:

1. A power plant which comprises a first compressor which receives air from the atmosphere, a second compressor, a heat exchanger, a conduit for passing the compressed air from the first compressor into the second compressor, means for passing the air compressed in the second compressor through the heat exchanger, combustion heating means for using a part of the compressed air from the heat exchanger for burning fuel, a turbine, means for passing the combustion gas to the turbine, a shaft for driving a load, gear means connecting said turbine with said shaft, a second turbine for driving at least one of said compressors, means for passing another part of the compressed air from the heat exchanger in heat-exchange contact with the combustion gas and into the second turbine, and adjustable gear means interconnecting both turbines.

2. A power plant according to claim 1 which comprises a valve-controlled bypass for passing a part of the air compressed in the first compressor back into the intake of said first compressor.

3. A power plant which comprises a first compressor which receives air from the atmosphere, a second compressor, a heat exchanger, a conduit for passing the compressed air from the first compressor into the second compressor, means for passing the air compressed in the second compressor through the heat exchanger, combustion heating means for using a part of the compressed air from the heat exchanger for burning fuel, a turbine, means for passing the combustion gas to the turbine, a shaft for driving a load, gear means connecting said turbine with said shaft, a second turbine for driving at least one of said compressors, means for passing another part of the compressed air from the heat exchanger in heat-exchange contact with the combustion gas and into the second turbine, an hydraulic coupling with adjustable speed means, and shaft means connecting the second turbine to the hydraulic coupling and to the gear means, whereby both turbines are connected to the load shaft and to each other.

WALTER TRAUPEL.
